UNITED STATES PATENT OFFICE.

BENJAMIN W. JONES, OF SCHENECTADY, NEW YORK, ASSIGNOR TO GENERAL ELECTRIC COMPANY, A CORPORATION OF NEW YORK.

CONTROL OF ELECTRIC MOTORS.

1,347,781.

Specification of Letters Patent. Patented July 27, 1920.

Application filed May 20, 1918. Serial No. 235,437.

To all whom it may concern:

Be it known that I, BENJAMIN W. JONES, a citizen of the United States, residing at Schenectady, in the county of Schenectady, 5 State of New York, have invented certain new and useful Improvements in Control of Electric Motors, of which the following is a specification.

This invention relates to the control of 10 electric motors and has for its object the provision of improved means whereby a starting resistance may be automatically cut out of the motor circuit in a simple, reliable and efficient manner.

15 My invention relates more specifically to the starting of an alternating current motor of the wound rotor type in which a resistance is employed to bring the motor up to speed gradually and safely. My invention 20 finds a ready application in the starting of three-phase motors, particularly where at starting the resistance sections are connected in delta. One of the objects of my invention is to provide means whereby a resistance 25 so connected may be reduced in such a manner that all of the resistance is in circuit during the starting period and the total resistance is reduced gradually and at a proper rate. In carrying out my invention in one 30 form, I first connect the resistance sections in delta to give the maximum resistance. When the motor current drops to a predetermined value the intermediate points of the three legs are connected together, thereby 35 making what might be called a multiple Y connection, each leg being formed by two halves of the leg connected in multiple. This reduces the resistance by a definite percentage. The next step, which in the par- 40 ticular arrangement shown will be taken when the current drops to the predetermined value, consists in breaking the connection of the intermediate points to each other and connecting these intermediate points to the 45 ends of the sections, the intermediate point of each section being connected to the point of connection of the other two legs. This makes what might be called a multiple delta connection, since the connection will now be 50 a delta in which each leg is composed of two halves of a leg connected in multiple, and the resistance will be again reduced. The final step which will be taken at the proper time consists in restoring the first intermedi- 55 ate step while maintaining the second inter-

mediate step, the result being to short circuit each leg and entirely short circuit the rotor. Further objects and purposes of my invention will appear in the course of the following specification, in which I have 60 shown my invention embodied in concrete form for purposes of illustration.

In the accompanying drawing illustrating one form of my invention Figure 1 is a diagrammatic view of a system of control 65 for an alternating current motor, and Figs. 2, 3, 4 and 5 show how the resistance sections are connected in the various steps.

Referring to the drawings, M represents 70 a motor to be controlled and in the arrangement shown is a three phase slip ring motor to which are permanently connected the resistance sections R, R' and R''. The permanent connections to the slip rings are made in delta although this connection is not es- 75 sential to my invention. Electro-magnetic switch or contactor 10, controlled by a man- ually operated switch 11, is arranged to con- 80 nect the motor to the line. Contactor 12, which is the first to close after the closure 85 of switch 10, makes the connection of the resistance sections shown in Fig. 3 and con- tactor 13, which closes after switch 12, makes the connections of the resistance section shown in Fig. 4. The final step which is 90 accomplished by the closure of switch 12, while switch 13 is closed, establishes the connection of the resistance shown in Fig. 5. The closure of switches 12 and 13 is under 95 the control of the motor current, and to this end I provide the two current limit relays 14 and 15. The closure of contactor 12 is under the control of the current limit relay 14 and the closure of contactor 13 is under 100 the control of current limit relay 15. Cur- rent limit relay 14, therefore, operates twice in a starting cycle, since the contactor 12 closes twice. The connections between the contactors 12 and 13 are such that when the contactor 13 closes the contactor 12 opens to 105 establish the connections shown in Fig. 4, and when the current drops to a predeter- mined value the contactor 12 will again close while the contactor 13 remains closed.

Referring now to the specific connections, 110 it will be noted that the contactor 10 is pro- vided with an interlock 16, one contact of which is connected to the winding of con- tactor 12 while the other is connected to a contact of the series relay 15. Closure of

the contactor 10, therefore, energizes the contactor 12 when the current drops to a predetermined value and the series relay 14 drops. The contactor 12 is provided with three interlocks one of which, 17, opens the actuating circuit of the contactor 13, while interlock 18 makes a maintaining circuit for the contactor 12, independently of the current limit relay 14. The interlock 19 makes a circuit for the shunt core of relay 15. Contactor 13 is provided with two interlocks, 21 and 22 for purposes hereinafter described. The two current limit relays 14 and 15, are of substantially the same type, the former consisting of a series winding controlling a contact 23 in the controlled circuit, the contact being normally raised so as to be ready for connection and released by a shunt coil 24 operating upon a pivoted lever 25, the end of which supports the contact 23. This is a well known form of current limit relay and requires no description. The current relay 15 differs from current relay 14 in merely that there are two contacts 26 and 27, one of which is closed when the relay is in its raised position and is open in its lower position by reason of the drop of the current. There is also provided a contact 20 for purposes hereinafter described.

As thus constructed and arranged the operation of my improved system is as follows: In the drawings the parts are all shown in the positions which they assume when the control switch 11 is open. To start the motor the control switch 11 is closed, thereby completing the circuit from line *a* through the winding of contactor 10 to line *b*; contactor 10 thereupon closes and completes the motor circuit. The connections of the resistance sections R , R' and R'' are now the permanent connections, which is a delta connection, shown in Fig. 2. The closure of contactor 10 connects the winding 12 to one side of the line and energizes the shunt winding 24 of the current limit relay 14, thereby releasing the contact 23 to the control of the series winding. When the current drops to the proper value, due to the speeding up of the motor, the contact 23 will drop and the circuit for the contactor 12 will be completed from the line *a*, conductor 28, through the upper contact of the series relay 15, through the interlocking contact 16, winding of contactor 12, and through the contact 23 to line *b*. The closing of the relay contact 23 short circuits the shunt winding 24 of the relay so that the contact 23 will be again raised, but in the meantime the contactor 12 having closed, makes a maintaining circuit for the contactor through the interlock 18 and conductor 29 independently of the relay contactor 23. The closing of the contactor 12 makes the connections shown in Fig. 3, in which it will be observed that the intermediate

points of the resistance are connected together. I have shown the intermediate point of the resistance as being the middle point although in practice this is not essential; in fact, in many cases it may be advisable to have one part greater than the other. The connections to the contactor 12 whereby the intermediate points are connected together will be clear from Fig. 1.

In order to illustrate how the value of the total resistance in circuit is reduced in the various steps, I shall assume the value of two for each of the resistance sections R , R' and R'' . Since as shown, the intermediate connection is at the middle point, each half section will have a value of one. The first step, with the contactor 10 only closed, and the resistance in full delta, the resultant three-phase resistance will be one-half of 1.33 as is well understood. When the second step is taken and the connection shown in Fig. 3 established, the resultant three phase resistance will be reduced to one-half of one, so that the closing of the contactor 12 has reduced the resistance in the ratio of 1.33 to 1, all the resistance being in circuit.

Proceeding now to the next step, the closing of the contactor 12 energizes the shunt coil of the current limit relay 15, thereby releasing the relay to the control of the motor current, the circuit being from line *a*, through conductor 28, through the shunt coil, through the interlocking contact 19 of contactor 12 and interlocking contact 21 of contactor 13 to line *b*. The relay 15 is now, therefore, under the control of the motor current so that when the current drops to the proper value the plunger will drop and make the lower contact, thereby energizing the winding of the contactor 13, the circuit now being through conductor 28, contact 27 of the current limit relay, interlock 17 of contactor 12, which has now opened due to its winding being deenergized at contact 26, winding of contactor 13 and back to line *b*. The closing of contactor 13 makes the connections shown in Fig. 4, from which it will be seen that the intermediate point of each section is connected to the junction point of the other two resistances. This makes what may be called a double delta connection since each leg is now composed of the two halves of the leg connected in parallel. This connection will reduce the resultant three-phase resistance to one-half of .33, as is well understood. The connections to the contactor 13 whereby this is accomplished will be obvious from Fig. 1. The closing of contactor 13 opens the circuit of the shunt coil of current limit relay 15 at the interlocking contact 21. The current limit relay will, therefore, make its upper contact in which the shunt winding of the relay 14 will be energized as before described, so that when the current drops to a predetermined value,

the contact 23 of the relay 24 will drop and establish a circuit for the winding of the contactor 12 from lines *a* through the conductor 28, upper contact of the relay 15 to the interlocking contact 16, winding of contactor 12 and the contact 23 of relay 14 at the other side of the line. The contactors 12 and 13 will now both be closed and connections will be established as shown in Fig. 5, 10 from which it will be seen that all of the resistance sections are short circuited. It will thus be seen that the total resistance in circuit is gradually reduced under the control of the motor current from a maximum in which the sections of resistance are connected in full delta to a minimum which in this case is a complete short circuit of the resistance, while maintaining all of the resistance in circuit during the cycle. Moreover, the current is kept balanced in all the 20 phases. The result is that a most efficient use is made of the resistance and the steps are properly graduated. It will also be noted that a minimum number of contactors are used, since one of the contactors, 25 namely contactor 12, is used twice.

While I have described my invention as embodied in concrete form and as operating in a specific manner in accordance with the 30 provisions of the patent statutes, it should be understood that I do not limit my invention thereto as various modifications will suggest themselves to those skilled in the art without departing from the spirit of my 35 invention, the scope of which is set forth in the annexed claims.

What I claim as new and desire to secure by Letters Patent of the United States, is:—

1. The combination with a three-phase 40 motor and a resistance section for each phase connected together at their ends of means automatically operated responsively to the motor current for connecting an intermediate point of each of said resistance sections to intermediate points of the other sections and then connecting the intermediate points to the ends of the sections while maintaining all the resistance in circuit to reduce the resistance in the motor circuit.

50 2. The combination with a three-phase motor and resistance sections having a delta connection thereto of means automatically operated responsively to the motor current for connecting an intermediate point of each 55 of said sections to an intermediate point of each of the other sections and then connecting each intermediate point to the ends of the other sections while maintaining all the resistance in circuit to reduce the resistance in the motor circuit.

60 3. The combination with a three-phase motor and resistance sections having a delta connection thereto of means for connecting an intermediate point of each of said sections to an intermediate point of each of the

other sections to reduce the resistance in the motor circuit.

4. The combination with a three-phase motor and resistance sections having a delta connection thereto of means for first connecting an intermediate point of each of said sections to an intermediate point of the other sections to reduce the resistance, and then connecting the three intermediate points to the ends to further reduce the resistance 75 in the motor circuit.

5. The combination with a polyphase motor and a resistance section connected to each phase and connected together at their ends, of means for connecting an intermediate point of each of said resistance sections to the ends of the other two sections while maintaining all of the resistance in circuit to reduce the total resistance in the 80 motor circuit.

6. The combination with a polyphase motor and a resistor connected to each phase the resistors being connected together at their ends, of means for connecting two parts of each resistor in parallel with the ends of each section thus formed of two parallel parts joined to reduce the total resistance in the motor circuit.

7. The combination with a three-phase motor and three resistors having a delta connection thereto, of means for connecting two parts of each resistor in parallel and connecting the sections thus formed of the parallel parts together at a common point to form a Y connection.

8. The combination with a three-phase motor and three resistors having a delta connection thereto, of means for connecting two parts of each resistor in parallel with the ends of the sections thus formed of the parallel parts joined to form a delta connection to reduce the resistance in the motor circuit.

9. The combination with a three-phase motor and three resistors having a delta connection thereto, of means for connecting two parts of each resistor in parallel and connecting the three sections thus formed of the parallel parts successively in Y and in delta to reduce the total resistance in the 115 motor circuit.

10. The combination with a three-phase motor and resistance sections having a delta connection thereto of means for first connecting intermediate points of said sections together to reduce the resistance, then breaking this first connection and connecting the intermediate points to the ends to further reduce the resistance, and finally restoring the first connection while maintaining the 120 second connection to short circuit the resistance.

11. The combination with a three-phase motor and resistance sections having a delta connection thereto of means for first con- 130

- necting an intermediate point of each of said sections to an intermediate point of each of the other sections to reduce the resistance, and subsequently connecting the intermediate point of each section to the ends of the other section with the first connection maintained to short circuit the resistance.
12. The combination with a three-phase motor and a resistance section for each phase connected together at their ends, of two electromagnetic switches for controlling said resistance and connections whereby one of said switches closes to connect intermediate points of said resistance sections together followed by the closure of the second switch and the opening of the first switch to connect the intermediate points to the ends of the sections, and finally the two switches close to short circuit the resistance.
13. The combination with a three-phase motor and resistance sections having a delta connection thereto, of two electromagnetic switches for controlling said resistance, and connections whereby closing one of said switches connects an intermediate point of each of said sections to an intermediate point of each of the other sections, closing the second switch and opening the first connects the intermediate point of each section to

the ends of the other sections, and finally closing the first switch with the second maintained closed short circuits the resistance sections.

14. The combination with a three-phase motor and resistance sections having a delta connection thereto, of two electromagnetic switches for controlling said resistance, means responsive to the motor current for controlling the said switches, and connections whereby the first of said switches will automatically close and connect an intermediate point of each of said sections to an intermediate point of each of the other sections when the current drops to a predetermined value, next the second of said switches will automatically close and the first automatically open to connect the intermediate point of each section to the ends of the other sections when the current drops to a predetermined value, and finally the first switch will automatically close and the second switch be maintained closed to short circuit the resistance sections when the current again drops to a predetermined value.

In witness whereof I have hereunto set my hand this 17th day of May, 1918.

BENJAMIN W. JONES.
